UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, ENGLAND, A BRITISH COMPANY.

FUSE-SETTING DEVICE FOR PROJECTILES.

Application filed July 26, 1927, Serial No. 208,477, and in Great Britain June 17, 1926.

This invention relates to fuse setting devices for projectiles, particularly projectiles for use in anti-aircraft guns, and has for its chief object to provide a device by which the 5 setting of the fuse or fuses of one or more projectiles can be varied in accordance with the changing conditions up to the moment at which a projectile is to be loaded into the gun.

10 According to the invention a container for the reception of one or more projectiles is provided with two rotary members adapted to engage with portions of the fuse body and of the adjustable fuse ring and means are provided for angularly displacing one of 15 these members with respect to the other in accordance with the fuse setting required at any particular moment, further means being provided for angularly displacing both of 20 the said members when a fresh projectile is inserted into the container so as to cause the said members to co-operate with the engaging portions of the fuse body and of the adjustable fuse ring in whatever position these 25 portions may be and then bring both of the said members to a definite position so that the fuse is then correctly set and can continue to be maintained correctly set by the continued displacement of the separately actuated member referred to above. This 30 separately actuated member is preferably the one that engages with the adjustable ring of the fuse and the aforesaid movements of the two members together and the separate movements of the member engaging with the adjustable fuse ring are preferably effected by 35 two separate crank handles or hand wheels associated with each other and with the mechanism for operating the said members, by means of a differential gear. The said 40 separately actuated member may be provided with two spring catches adapted to engage one on each side of a pin or projection on the adjustable fuse ring and the other member 45 may be provided with a spring plunger adapted to engage with a recess in the fuse body.

In order that the said invention may be clearly understood and readily carried into effect, the same will now be described more fully with reference to the accompanying drawings, in which:

Figure 1 is a side elevation showing a constructional form of the invention,

Figure 2 is a section taken approximately on the line 2, 2 of Figure 1, 55

Figure 3 is a vertical section on two planes as indicated by the line 3, 3 in Figure 2.

Figure 4 is a section taken approximately on the line 4, 4 of Figure 3.

Figure 5 is a side elevation, viewed at right angles to Figure 1, of the upper portion of the latter figure, 60

Figure 6 is an enlarged vertical section of the lower part of one of the containers and its associated parts, 65

Figure 7 is a section on the line 7, 7 of Figure 6, and

Figure 8 is a section on the line 8, 8 of Figure 6.

In the example shown A is a fixed container 70 provided with four compartments A¹, A¹—(there may, however, be more or fewer as required) for the reception of a corresponding number of projectiles (which in the example shown form part of cartridges B, B— 75 but which might be separate from the cartridge cases) and these compartments are vertical to receive the cartridges with the noses of the projectiles downwards. The said compartments are arranged equidistantly around a central vertical shaft C to the lower part of which is keyed a gear wheel C' meshing with four wheels C², C²—arranged co-axially with the containers and made hollow to receive the fuses of the projectiles. The noses of the fuses are supported in recessed parts A², A²—of the base of the container A. Each of the said hollow gear wheels is provided with two spring catches C³, C³ (Figure 7) adapted to engage one on 90 each side of a pin or projection b¹ on the adjustable fuse ring B' and each formed with an inclined surface C^{3x} with which the pin b¹ engages (if it is not situated between the said catches) during relative movement between the gear wheel C² and the adjustable fuse ring so as to permit the said pin to assume the position shown in Figure 7 between the two catches. The said catches are also 95 formed with other inclined surfaces so that the catches will be pressed back if the pin b¹ engages with the head portion of either catch during the insertion of a cartridge.

The central shaft C carries near its upper end the planet pinion carrier C⁴ of the aforesaid differential gear, the sun wheels C⁵, C⁶ of 100

105

which are connected to pinions C^{5x} , C^{6x} . The pinion C^{5x} engages with a gear wheel D driven by the handle D^1 (herein termed the setting handle) for setting the adjustable fuse rings B^1 , B^2 —and the pinion C^{6x} engages with a gear wheel E operated by another handle E^1 which is herein termed the equalizing handle. The latter gear wheel also engages with a pinion E^2 on a hollow shaft E^3 surrounding the aforesaid central shaft C , the lower end of this hollow shaft being keyed to a toothed wheel E^4 meshing with a second series of toothed wheels E^5 , E^6 —which are made hollow to receive the heads of the projectiles, each wheel of this second series having a spring plunger e^5 adapted to engage in a recess b^2 formed in the body B^2 of the fuse. The parts are so arranged that by turning the equalizing handle E^1 through a complete revolution the hollow gear wheels C^2 , C^2 —engaging with the adjustable fuse rings and the hollow gear wheels E^5 , E^6 —engaging with the fuse bodies are given a complete revolution in opposite directions so that when a fresh cartridge case has been inserted into its compartment (the pin b^1 in all probability not being between the catches C^3 , C^3 and the spring plunger e^5 not engaging in the recess b^2) the aforesaid spring catches C^3 , C^3 and the aforesaid spring plunger e^6 will engage with the projection b^1 on the adjustable ring and with the recess b^2 in the fuse body respectively at some portion of the rotation of the handle E^1 and by bringing this handle to the original position all the hollow gear wheels will be brought back to the position they previously occupied, assuming that the setting handle D^1 has not been moved during this short interval of time, and the fuse of the new cartridge will thus have been correctly adjusted. If during the said interval of time the setting handle D^1 has been adjusted to a new fuse setting the movement of the equalizing handle E^1 to its original position will, of course, displace the hollow gear wheels E^5 , E^6 —appertaining to the adjustable fuse rings to the position determined by the new position of the setting handle D^1 . It will thus be seen that when a new cartridge has been inserted into its compartment, the actuation of the equalizing handle E^1 , which is at once effected, serves to adjust the time fuse of that cartridge in accordance with the particular conditions prevailing at the moment, the actuation of the setting handle D^1 then varying the fuse setting of all the cartridges simultaneously as the said conditions change. The normal position of the equalizing handle E^1 to which it must be brought at the end of each actuation is determined positively by suitable means such as a spring plunger e^1 carried by the said handle for engaging in a hole a^2 in a bracket A^2 on the container. It will be understood that the rotary movements

of the hollow gear wheels E^5 , E^6 —engaging with the fuse bodies causes bodily angular movements of the cartridges as these fuse bodies are rigidly attached to the projectiles. In the example shown one revolution of the equalizing handle E^1 gives one revolution to the hollow gear wheels C^2 , C^2 —and E^5 , E^6 in opposite directions, but if desired the gearing may be so designed as to require more than one revolution of the said handle.

The movements of the setting handle D^1 are preferably effected in accordance with indications transmitted from a control station or apparatus and for this purpose this handle is connected by gearing to a dial D^2 (graduated for the fuse settings) over which moves a pointer D^3 suitably operated from the control station or apparatus where the fuse setting is determined and the said setting handle is constantly operated in order to cause an index mark d^2 on the dial to follow the movements of the said pointer D^3 . The gearing for operating the dial D^2 comprises, in the example shown, a radial shaft D^4 having at its inner end a pinion d^4 meshing with the aforesaid pinion C^{5x} and having at its outer end a pinion d^5 meshing with a pinion d^6 on an upwardly extending shaft D^6 which drives the dial D^2 through suitable gearing. The setting handle D^1 is held by the fuse setting member during the operation of the equalizing handle E^1 , but if desired a locking device could be provided for the setting handle.

What we claim and desire to secure by Letters Patent of the United States is:—

1. A fuse setting device for projectiles, comprising a container for the reception of a projectile, a member carried by said casing and adapted to engage with part of the fuse body, a member carried by said casing and adapted to engage with part of the adjustable portion of the fuse, an actuating device for each of said members, mechanism between each device and its particular member and a differential gear associated with said devices and said mechanisms.

2. A fuse setting device for projectiles, comprising a container for the reception of a projectile, a member in the form of a hollow gear wheel for receiving the fuse of the projectile, another member in the form of a hollow gear wheel for receiving the fuse of the projectile, co-acting means between one of these members and the fuse body, co-acting means between the other member and the adjustable portion of the fuse, an actuating device for each of said members, mechanism between each device and its particular member and a differential gear associated with said devices and said mechanisms.

3. A fuse setting device for projectiles, comprising a container for the reception of a projectile, a member carried by said casing,

- a spring plunger on said member adapted to engage with a recess in the fuse body, a second member carried by said casing, spring catches on said second member, said catches being adapted to engage one on each side with a projection on the adjustable ring of the fuse, an actuating device for each of said members, mechanism between each device and its particular member and a differential gear associated with said devices and said mechanisms.
4. A fuse setting device for projectiles, comprising a container for the reception of the projectile, a member carried by said casing and adapted to engage with part of the fuse body, a member carried by said casing and adapted to engage with part of the adjustable portion of the fuse, an indicator operated from a control station and giving the fuse settings, said indicator forming part of the fuse setting device, means for angularly displacing one of the said members in accordance with the indications of said indicator, and means for angularly displacing both of the said members when a fresh projectile is inserted into the container so as to cause the said members to cooperate with the engaging parts of the fuse body and of the adjustable portion of the fuse in whatever position these parts may be and then bring both the said members to a definite position so that the fuse is then correctly set and can continue to be maintained correctly set by the continued displacement of the separately actuated member.
5. A fuse setting device for projectiles, comprising a container having a plurality of compartments each receiving a projectile, a member contiguous to each compartment for engaging with part of the fuse body of the projectile in that compartment, a second member contiguous to each compartment for engaging with part of the adjustable portion of the fuse of the projectile in that compartment, an actuating device for each group of said members, mechanism between each device and its particular group of members and a differential gear associated with said devices and said mechanisms.

ARTHUR TREVOR DAWSON.
GEORGE THOMAS BUCKHAM.
